[57] CLAIM

The ornamental design for an ignition analyzer, substantially as shown and described.

DESCRIPTION

FIG. 1 is a front elevational view of an ignition analyzer showing my new design;

FIG. 2 is a right side elevational view thereof, the left side being a mirror image thereto;

FIG. 3 is a rear elevational view thereof;

FIG. 4 is a top plan view thereof;

FIG. 5 is a bottom plan view thereof;

FIG. 6 is a front elevational view thereof with the handle in a fully extended position;

FIG. 7 is a right side elevational view of FIG. 6, the left side being a mirror image thereto;

FIG. 8 is a top plan view of FIG. 6;

FIG. 9 is a bottom plan view of FIG. 6;

FIG. 10 is a rear elevational view of FIG. 6;

FIG. 11 is a right side elevational view of FIG. 6 in a sitting position; and

FIG. 12 is a right side elevational view of FIG. 6 in another sitting position.
